UNITED STATES PATENT OFFICE.

BERT R. BENJAMIN, OF OAK PARK, ILLINOIS, ASSIGNOR TO INTERNATIONAL HARVESTER COMPANY OF NEW JERSEY, A CORPORATION OF NEW JERSEY.

GRAIN-BINDER.

1,241,490.

Specification of Letters Patent.

Patented Oct. 2, 1917.

Application filed May 11, 1914, Serial No. 837,682. Renewed March 28, 1917. Serial No. 158,119.

To all whom it may concern:

Be it known that I, BERT R. BENJAMIN, a citizen of the United States, residing at Oak Park, in the county of Cook and State 5 of Illinois, have invented certain new and useful Improvements in Grain-Binders, of which the following is a full, clear, and exact specification.

My invention relates to grain binders.

- 10 In my prior Patent No. 994,711, patented June 18, 1911, I have described and claimed a clutch controlling mechanism for a binder wherein the shaft carrying the compressor or binder trip of the binder, upon the actuation 15 of that trip, is moved bodily to disengage from the rotating finger of the binder clutch a slidable clutch controlling member operatively connected to the shaft, this clutch controlling member being automatically held out of engagement with the clutch finger by a coöperating cam mechanism to permit a third revolution of the binder clutch and the operation of the sheaf binding and discharging mechanism.
- 20 My present invention has for its object to improve and simplify the construction of such a mechanism in such a manner as to increase its efficiency by rendering it more sure in its operation and reducing the amount of wear upon the parts. A further object of my present invention is to provide a sliding trip mechanism of the type covered by that patent especially adapted to use in connection with a shocking machine 25 having a movable sheaf delivery member, means being provided for controlling the binder mechanism in accordance with the requirements of such a shocker; *i. e.*, for interrupting the sheaf discharging mechanism on the binder at a fractional point in its cycle of operation until the sheaf delivery member of the shocker is in position to receive the sheaf discharged by that mechanism.
- 40 I attain these objects by providing improved mechanism for controlling the binder clutch whereby, when adapted to use in connection with a binder alone, the general efficiency of the device is increased as outlined above and whereby, when used in connection with a shocker of the character men-

tioned, the mechanism is adapted to control the binder clutch, locking and unlocking the same at a point intermediate the ends of the normal cycle of operation of the binding 55 and discharging mechanism, in timed relation with respect to the movable sheaf delivery member of the shocker.

In order that my invention may be clearly and fully disclosed, I have shown for purposes of illustration in the accompanying drawings two embodiments which it may assume in practice, illustrating the same as adapted to use in connection with a shocker of the well-known Raney type.

In these drawings—

Figure 1 is a front elevation of a binder equipped with my improvements and having a shocker operatively connected thereto, certain of the parts being omitted to facilitate 70 clearness of illustration;

Fig. 2 is a side elevation of the clutch controlling mechanism looking at the same from the sheaf delivery side of the binder;

Fig. 3 is a detail view of a part of the 75 construction shown in Fig. 1, showing more clearly and in an enlarged view the mounting of the compressor shaft and the connection of the clutch controlling member thereto;

Fig. 4 is a detail front elevation of a modified form of the clutch controlling mechanism shown in Fig. 1.

The binder shown is of standard construction comprising a machine frame 1 having 85 a binder deck 2 supported thereon by suitable supports 3, a binder frame 4, a breast-plate 5, a binding needle 6 carried on the needle shaft 7 journaled on the frame, discharge arms 8 carried on a knotter shaft 9, 90 packers 10 carried on a packer shaft 11, a clutch 12 having a movable clutch finger 13, and a compressor shaft 14 having a trip 15 connected thereto and normally extending upward through the deck 2, all of these 95 parts being operatively connected and operating in a well-known manner, the compressor shaft 14 being movable with the trip 15 in a slot 16 in an extension on the lower end of the frame 4, and connected, 100 through a link 17, to an arm 18 operable by the cam wheel mechanism 19, while the

needle 6 is connected, through a crank 20 and a link 21, to a lug 22 rotatable with this cam wheel, as described in my patent mentioned above.

As in the manner described in that patent, when the trip 15 is forced downward and backward toward the full line position shown in Fig. 1 by the grain packed against it by the packers 10, a sliding trip member 23, 10 movable longitudinally through a stud 24 on the front of the frame 4, is withdrawn from its normal position in the path of the rotatable finger 13 of the clutch 12 so that this clutch may connect the sheaf binding and 15 discharging mechanism. In that patent the clutch controlling member extends part way around the shaft 14 and has an upwardly extending curved tail portion engageable with a cam movable with the needle crank, 20 and at its upper end connected only to a spring mechanism carried on the frame which normally holds this clutch controlling member in contact with that cam, the compressor shaft 14 when moved bodily stubble- 25 wardly by the actuation of its trip, withdrawing the clutch controlling member from engagement with the clutch, and the cam holding that member out of engagement in such a manner that the latter can complete 30 its third revolution. In my present construction, however, the member 23 is in the form of a flat strap having its stubbleward end 25 hooked around the lower end of a normally vertically disposed member 26 piv- 35 oted at 27 at its upper end to the frame 4 and pivoted on the shaft 14 at a point be- 40 tween its connection to the strap end 25 and its pivot on the frame. This member is also provided with a projection 28 on its lower 45 end extending laterally from a point adja- 50 cent its pivot on the shaft 14, which projec- 55 tion is engageable with a cam 29 movable with the needle crank 20. Further, in lieu 60 of the spring connection directly between 65 the frame and the free end of the clutch con- 70 trolling member as described in my prior 75 patent, in this construction I provide a 80 spring and rod connection 80 between the 85 member 26 and the frame 4 at a point pre- 90 ferably between the pivots of this member 26. 95 Further, I provide a stop 31 on the upper 100 end of this member 26 adapted to engage 105 with a co-operating stop 32 on the frame 4 to 110 limit the movement of the member.

In adapting my invention to use in connection with a grain shucker of the type wherein a swinging sheaf delivery member is used, it is desirable that means be provided for interrupting the connection of the 115 binder clutch at a point intermediate the ends of the normal cycle of operation of the sheaf binding and discharging mechanism, preferably after the latter has moved through approximately two-thirds of its cy- 120 cle of operation; *i. e.*, after the sheaf has

been bound and the sheaf discharging mechanism has moved through a portion of its operation but before that discharging mechanism has completed its operation. In adapting my construction to such a use 70 (referring first to Fig. 1) I provide a sec- 75 ond normally operative clutch controlling member 33, which is also preferably in the form of a flat strap slidable through a sec- 80 ond stud 34, in this instance formed on the frame 4 at a point beneath the stud 24. This strap extends stubblewardly and then up- 85 wardly, where its upper end, as shown at 90 35 (Fig. 2) is bent around the upper end of a crank 36 resiliently mounted at 37 upon the under side of the binder deck 2 and having a rearwardly and downwardly extending shank 38, pivotally connected at 39 to a stub- 95 blewardly extending link 40, which is, in turn, pivotally connected at 41 to a binder lock operating or tripping member 42, piv- 100 oted at 43 on a standard 44 carried on a sup- 105 port 45, which protrudes stubblewardly be- 110 neath the binder deck 2 and normally acts as a support for the swinging sheaf delivery member 46 of the shucker when said mem- 115 ber is in sheaf receiving position. It is thus seen that when the fork or sheaf delivery member 46 of the shucker depresses the tri- 120 pping member 42 to the dotted line position shown in Fig. 1, the effect of this movement is to withdraw the clutch controlling mem- 125 ber 33 from its normal or clutch engaging position shown in Fig. 1, wherein it is held by the spring 37. However, it is necessary 130 that this clutch controlling member 33 co- 135 operate with the clutch controlling member 23 and operate in timed relation therewith so that while the member 23 controls the binding of the sheaves, the member 33 acts 140 to interrupt the completion of the discharge 145 of the sheaves until the sheaf delivery mem- 150 ber 46 has returned to the dotted line posi- 155 tion shown in Fig. 1 and depressed the trip 160 42. I accordingly connect these two mem- 165 bers 23 and 33 by means of a slotted link 47 pivotally connected at its grainward end at 48 to the free end of the crank on the end of the compressor shaft 14 and slidably con- 170 nected at its stubbleward end to the mem- 175 ber 36 through a longitudinally extending slot 49.

In the operation of this embodiment of my invention in connection with a shucker, it is to be understood that the sheaf delivery 180 member 46 of the shucker normally occupies the lower dotted line position shown in Fig. 1, wherein it depresses the trip 42, and that when a sheaf is delivered thereto by the sheaf discharge arms 8 of the binder, this 185 sheaf actuates suitable controlling mechanism; as, for instance, a trip 50 operatively connected to the operating mechanism of the sheaf delivery member (not shown), the sheaf delivery member being moved back 190

and forth by this operating mechanism into and out of engagement with the trip 42 as it delivers the sheaves. Obviously, in the first operation of the mechanism; *i. e.*, when 5 the sheaf delivery member and other parts are in the normal or dotted line position shown and the grain first commences to be delivered to the packers 10, the supplemental clutch controlling member 33 will be 10 held out of engagement with the clutch finger 13 due to the depression of the trip 42 and the connection of the clutch controlling member to that trip, so that the first sheaf will be bound and discharged to the sheaf 15 delivery member 46 in the usual manner, the binder parts returning to their usual positions after the discharge of a sheaf, as shown in dotted lines in Fig. 1, the sheaf discharging arms 8 occupying their upper 20 dotted line position and the clutch controlling member 23 being in engagement with the clutch finger 13. As this first sheaf has, however, actuated the tripping mechanism 50 for the fork and the latter moves up from 25 its lower dotted line position, the trip 42 will obviously be raised by the spring 37 to the full line position shown and the clutch controlling member 33 will also be returned to its normal or operative position, but will 30 perform no function due to the engagement of the member 23 with the clutch finger. With the parts thus positioned, the packers 10 then proceed to pack the grain for the next sheaf against the compressor trip 15 35 until this trip is forced backward by the pressure of the grain, whereupon, through the connection of the clutch controlling member 23 to the compressor shaft 14, this clutch controlling member 23 is withdrawn 40 from engagement with the clutch finger 13 and the binding operation begins. During the whole of this binding operation the clutch controlling member 23 will be held out of engagement with the clutch finger 13 45 by the cam 29 so that, so far as the member 23 is concerned, the clutch finger could rotate through its normal three revolutions. However, through the connections of the member 33, the latter is thrown into the path 50 of this clutch finger 13 after that finger starts on its second revolution in such a manner that it will interrupt the connection of the clutch after the clutch finger has completed its second revolution; *i. e.*, when the 55 sheaf discharge arms 8 have completed substantially two-thirds of their normal cycle of operation and occupy the lower dotted line position shown in Fig. 1. In this position, with the sheaf bound and the discharge 60 arms 8 resting against the sheaf ready to discharge it, the parts will remain until the sheaf delivery member 46 returns into engagement with the trip 42 and depresses the latter, whereupon the clutch controlling 65 member 33 will be again withdrawn from

engagement with the clutch finger 13 through the connection of the clutch and the discharging mechanism to the latter, and the arms 8 will be permitted to complete their movement, moving through the last 70 third of their cycle of operation and discharging the sheaf upon the sheaf delivery member then waiting to receive it.

In Fig. 4 I have illustrated a modified form of the construction shown in Figs. 1 and 2, wherein the device is constructed substantially in accordance with the embodiment hereinabove described, but in which, instead of the slotted connection between the member 36 and the crank on the compressor shaft being adjacent the former member, it is provided adjacent the crank, a connecting strap 51 being used, which has its outer end bent around the upper end of the member 36 at 52 and has a loop 53 provided thereon in such a manner as to form a slot. In this construction the member 51 acts also to perform the function of the clutch controlling member 33, and also has its inner or clutch engaging end bent upward, as shown at 54, 85 so that it may pass through the same lug 24 which acts as a guide for the upper clutch controlling member 23, the two members being worked back and forth above or beneath each other by the connecting mechanism in the same sequence as that heretofore described in connection with the embodiment of my invention shown in Fig. 1. It is also to be noted that in this construction the secondary clutch controlling member 90 also acts to interrupt the rotation of the clutch finger 13 at a point substantially at the end of the second revolution of the latter rather than at a point a trifle beyond the end of this revolution, as is the case 100 when a construction of the type shown in Fig. 1 is employed.

While I have in this application specifically described two embodiments which my invention may assume in practice, it is, of course, to be understood that the forms shown herein are used for purposes of illustration and the invention is not necessarily limited to embodiment in these forms, the spirit of the invention being capable of being adapted 115 to use in other forms.

What I claim as my invention, and desire to secure by Letters Patent, is:

1. In a binder, a frame, a compressor trip, a shaft movable bodily with respect to said frame upon actuation of said trip, and means operatively connecting said frame and shaft movable about a fixed axis on said frame.
2. In a binder, a frame, a compressor shaft movable bodily with respect thereto, and a link pivotally connected directly between said frame and said shaft for connecting the latter to said frame.
3. In a binder, a frame, a compressor

shaft movable bodily with respect thereto, a single rigid means pivotally connecting said frame and shaft and movable about its pivot on the former, and a resilient connection between said rigid means and said frame.

4. In a binder, a frame, a compressor shaft movable bodily with respect thereto, a link pivotally connected directly between 10 said frame and said shaft for connecting the latter to said frame, and means for moving said shaft bodily with respect to said frame.

5. In a binder, a frame, a compressor shaft movable bodily with respect thereto, 15 a needle shaft, a member pivoted at its opposite ends directly to said frame and compressor shaft, and means on said needle shaft for moving said member and compressor shaft with respect to said frame.

20 6. In a binder, a frame, a compressor shaft bodily movable with respect thereto, a single member pivotally connecting said shaft and said frame, said member having a laterally extending projection thereon, and mechanism engageable with said projection for moving said shaft and member with respect to the frame.

7. In a binder, a frame, a compressor shaft movable bodily with respect thereto, 30 a member pivotally connected to said compressor shaft and said frame, a resilient connection between said member and said frame, and cam mechanism carried on said frame for adjusting said compressor shaft and member with respect thereto.

40 8. In a binder, a frame, a compressor shaft thereon movable with respect thereto, a member operatively connected to said compressor shaft and pivoted to said frame, means for moving said member and shaft laterally about the pivot of said member on the frame, and means on said member and frame coöperating to limit the movement of said member and shaft.

45 9. In a binder, a frame, a compressor shaft thereon movable laterally with respect thereto, a member operatively connecting said compressor shaft and frame, cam mechanism for moving said member and shaft laterally, means resisting such movement, and means for limiting such movement.

55 10. In a binder, a frame, a rock shaft movable bodily with respect thereto, a member pivoted to said rock shaft and operatively connected to said frame, a member having a hooked end operatively connected to said first mentioned member and slidably connected with said frame, and means on said frame for moving said first mentioned member and shaft bodily with respect to the frame.

60 11. In a binder, a frame, a rock shaft movable bodily with respect thereto, a member pivoted to said frame and operatively connected to said rock shaft, a member hav-

ing a hooked end operatively connected to said pivoted member and slidably connected with said frame, means on said frame for moving said first mentioned member and shaft bodily with respect to the frame, and means on said frame for limiting the movement of said member and shaft.

70 12. In a binder, a frame, a compressor shaft bodily movable with respect thereto, a member pivoted at one end to said shaft and at its opposite end to said frame, said member having a laterally extending projection thereon, mechanism engageable with said projection for moving said shaft and member with respect to the frame, and a resilient connection between said member and said frame normally holding said projection in engagement with said mechanism.

75 13. In a binder, a frame, a compressor shaft laterally movable with respect thereto, 80 a member pivoted at one end to said shaft and at its opposite end to said frame, mechanism engageable with said member for moving said shaft and member with respect to the frame, and a resilient connection operatively connected to said member at a point between its pivots and slidably connected to said frame.

85 14. In a binder, a frame, a compressor shaft bodily movable with respect thereto, 95 a member pivoted at one end to said shaft and at its opposite end to said frame, said member having a laterally extending projection thereon, mechanism engageable with said projection for moving said shaft and member with respect to the frame, and a resilient connection operatively connected to said member at a point between its pivots and slidably connected to said frame.

100 15. In a binder, a frame, a compressor shaft movable bodily with respect thereto, 105 a member pivoted on said compressor shaft and on said frame at a point above its pivot to said shaft, said member having an extension thereon at a point adjacent its pivot to the shaft, a slideable member carried by the frame and hooked over said extension, and means on said frame engageable with said pivoted member for moving the latter and said slideable member in a lateral direction.

110 16. In a binder, a frame, a compressor shaft thereon movable with respect thereto, 120 a swinging member pivoted to said compressor shaft and said frame, means for moving said member and shaft laterally about the pivot of said member on the frame, means on said member and frame coöperating to limit the movement of said member and shaft, and a resilient connection operatively connected between said member and frame 125 normally holding said member in engagement with the means for moving the same laterally.

130 17. In a binder, a frame, a compressor

- shaft bodily movable with respect thereto, a member pivoted at one end to said shaft and at its opposite end to said frame, said member having a laterally extending projection thereon, mechanism engageable with said projection for moving said shaft and member with respect to the frame, a resilient connection operatively connected to said member at a point between its pivots and 5 slidably connected to said frame, and means on said frame for limiting the movement of said member and shaft.
18. In a binder, a frame, a rock shaft movable bodily with respect thereto, a member pivoted to said rock shaft and frame, a member having a hooked end operatively connected to said first mentioned member and slidably connected with said frame, means on said frame for moving said first 15 mentioned member and shaft bodily with respect to the frame, means on said frame for limiting the movement of said member and shaft, and means operatively connected between said first mentioned member and 20 said frame normally holding the former in engagement with the means for moving it laterally.
19. In a binder, a frame, a compressor shaft movable bodily with respect thereto, a member pivoted on said compressor shaft and on said frame at a point above its pivot to said shaft, said member having an extension thereon at a point adjacent its pivot to the shaft, a slidable member carried by 25 the frame and hooked over said extension, means on said frame engageable with said member for moving the latter and said slid- 30 able member laterally, and resilient connections between said member and frame normally projecting said member in an opposite direction.
20. In a binder, a frame, a binder clutch thereon, clutch controlling mechanism therefor including a clutch controlling member, a supplemental clutch controlling member reciprocable with respect to said frame, and means for throwing said clutch controlling members alternately into engagement with 45 said binder clutch.
21. In a binder, a frame, a binder clutch thereon, a clutch controlling member, means for withdrawing said clutch controlling member whereby said clutch may normally make three revolutions, a supplemental sliding clutch member reciprocable with respect to said frame, and means for throwing the latter into engagement with said clutch prior to the completion of the normal cycle thereof.
22. In a binder, a frame, a binder clutch thereon, clutch controlling mechanism therefor including a clutch controlling member reciprocable with respect to said frame, supplemental clutch controlling 50 mechanism including a second clutch con-
- trolling member reciprocable with respect to said frame, operating mechanism for said clutch controlling members, and an operative connection between the same.
23. In a binder, a frame, sheaf binding and discharging mechanism thereon comprising a binder clutch and compressor trip, a compressor shaft movable bodily with said trip, clutch controlling mechanism including a clutch controlling member movable 70 with said shaft and slidable with respect to said frame, supplemental clutch controlling mechanism including a second slidable clutch controlling member, and a slidable link connection between said shaft and said 75 second clutch controlling member.
24. In a binder, a frame, a binder clutch thereon including a clutch controlling member, means for withdrawing said clutch controlling member from engagement with said clutch for a predetermined period, a supplemental clutch controlling member, means for actuating said supplemental clutch controlling member while said first mentioned clutch controlling member is withdrawn, 80 and coöperating means normally tending to throw said supplemental clutch controlling member into clutch engaging position.
25. In a binder, a frame, sheaf binding and discharging mechanism thereon comprising a binder clutch and compressor trip, a compressor shaft movable bodily with said trip, clutch controlling mechanism including a clutch controlling member movable 85 with said shaft and slidable with respect to said frame, supplemental clutch controlling mechanism including a second slidable clutch controlling member, an operative connection between said shaft and said second clutch controlling member, and means normally tending to throw said second clutch controlling member into clutch engaging position.
26. In a binder, a frame, sheaf binding and discharging mechanism thereon includ- 90 ing a binder clutch and a compressor trip, a clutch controlling member slidable on said frame operatively connected to said compressor trip and normally engageable with 95 said clutch, and means including a supplemental slidable clutch controlling member on said frame operatively connected to said trip and first mentioned slidable member and projectable into engagement with said clutch prior to the completion of the normal 100 operation of the same.
27. In a binder, a frame, sheaf binding and discharging mechanism thereon includ- 110 ing a binder clutch and a compressor trip, means operatively associated with said trip including a clutch controlling member slid- 115 able on said frame and supplemental clutch controlling means operatively connected to said trip including a second slidable clutch controlling member engageable with said 120
- 65 mechanism including a second clutch con- 130

- clutch alternately with respect to said first mentioned slidable member.
28. In a binder, a frame, sheaf binding and discharging mechanism thereon including a binder clutch and a compressor trip, means including a clutch controlling member slidable with respect to said frame operatively connected to said trip and disengageable from said clutch when said trip is depressed, and means operatively connected to said trip and slidable clutch controlling member comprising a coöperating slidable clutch controlling member projectable into engagement with said clutch after the latter has completed its second revolution.
29. In a binder, a frame, sheaf binding and discharging mechanism thereon including a compressor trip and a binder clutch, clutch controlling means including a clutch controlling member slidable with respect to said frame operatively connected to said compressor trip and withdrawable from engagement with said clutch upon actuation of said trip, and means including a second slidable clutch controlling member operatively connected to said first mentioned clutch controlling member and disposed beneath the same projectable into engagement with said clutch prior to the completion of the normal operation of the latter after said first mentioned clutch controlling member is withdrawn.
30. In a binder, a frame, sheaf binding and discharging mechanism including a binder clutch and a compressor trip, means including a sliding trip member normally in engagement with said clutch withdrawable upon depression of said trip, supplemental means for holding said slidable member out of engagement with said clutch during a plurality of revolutions of the latter, and means including a coöperating slidable clutch engaging member slidably connected with said first mentioned clutch controlling member and said trip projectable into engagement with said clutch after said clutch has completed a fractional part of its normal movement.
31. In a binder, a frame, sheaf binding and discharging mechanism comprising a binder clutch and compressor trip, a compressor shaft movable bodily with said trip, a slidable clutch controlling member movable with said shaft, a second slidable clutch controlling member, a slotted link connection between said shaft and said second clutch controlling member, and means for withdrawing said first mentioned slidable clutch controlling member from engagement with said clutch for a predetermined time and projecting said last mentioned clutch controlling member into engagement with said clutch after a fractional part of said time has elapsed.
32. In a binder, a frame, sheaf binding and discharging mechanism thereon including a binder clutch and a compressor trip, a compressor shaft movable bodily with respect to said frame, a slidable clutch controlling member movable with said shaft, cam mechanism for holding said clutch controlling member out of engagement with said clutch during a plurality of revolutions of the latter, a coöperating slidable clutch controlling member, and means including a slotted link connection operatively connected between said shaft and said coöperating slidable member for projecting the latter into engagement with said clutch after a fractional part of the rotation permitted by the withdrawal of said first mentioned clutch controlling member.
33. In a binder, a frame, sheaf binding and discharging mechanism including a binder clutch and a compressor trip, operative connections between said trip and clutch including a clutch controlling member, a supplemental clutch controlling member reciprocal with respect to said frame, operative connections between the same and said first mentioned clutch controlling member, a sheaf delivery member receiving sheaves from said binding and discharging mechanism, and means between said sheaf delivery member and said supplemental clutch controlling member and controlled by said sheaf delivery member for reciprocating said supplemental clutch controlling member.
34. In a binder, a frame, sheaf binding and discharging mechanism comprising a binder clutch and a compressor trip, a compressor shaft movable bodily with said trip, a slidable clutch controlling member movable with said shaft, a second slidable clutch controlling member, a slotted link connection between said shaft and said second clutch controlling member, means for withdrawing said first mentioned slidable clutch controlling member from engagement with said clutch for a predetermined time and projecting said last mentioned clutch controlling member into engagement with said clutch after a fractional part of said time has elapsed, and supplemental tripping mechanism operatively connected with said last mentioned clutch controlling member.
35. In a binder, a frame, sheaf binding and discharging mechanism comprising a binder clutch and a compressor trip, a compressor shaft movable bodily with said trip, a slidable clutch controlling member movable with said shaft, a second slidable clutch controlling member, a slotted link connection between said shaft and said second clutch controlling member, means for withdrawing said first mentioned slidable clutch controlling member from engagement with said clutch for a predetermined time and projecting said last mentioned clutch controlling member into engagement with said clutch after a fractional part of said time has elapsed.

trolling member into engagement with said clutch after a fractional part of said time has elapsed, supplemental tripping mechanism operatively connected with said last 5 mentioned clutch controlling member, and means for operating said last mentioned tripping mechanism.

In testimony whereof I affix my signature, in the presence of two witnesses.

BERT R. BENJAMIN.
